UNITED STATES PATENT OFFICE.

ERNEST R. JUNGLING, OF NEW YORK, N. Y.

SHEET-GAGE FOR ADDRESSING-MACHINES.

1,397,125.

Specification of Letters Patent. Patented Nov. 15, 1921.

Application filed August 8, 1921. Serial No. 490,584.

To all whom it may concern:

Be it known that I, ERNEST R. JUNGLING, a citizen of the United States, and a resident of the city of New York, county 5 of Kings, and State of New York, have invented a certain new and useful Improvement in Sheet-Gages for Addressing-Machines, of which the following is a specification.

10 This invention relates to a gage attachment for addressing machines, and has for its object to provide a device applicable to the well known forms of addressing machines, and adapted to aid in permitting the 15 placing of names and addresses on a sheet of paper. By means of my improved attachment it is possible to place a number of names and addresses on substantially large sheets of paper, such as loose leaf 20 sheets from address books or the like, with the names on one sheet corresponding in horizontal and vertical alinement with those on the other sheets, whereby a very neat and desirable appearance and arrangement 25 of each page is provided.

With these objects, and other objects which may hereinafter appear in view, I have devised the particular arrangement of parts hereinafter set forth and more particularly pointed out in the claims appended 30 hereto.

Reference is to be had to the accompanying drawing, forming part hereof, in which—

35 Figure 1 is a plan view of a well known form of addressing machine, showing the manner in which my improved sheet gage is applied thereto;

Fig. 2 is a perspective view of one of 40 the address plates;

Fig. 3 is an end view of the addressing machine, showing a portion of my improved sheet gage; and

Fig. 4 is a perspective view of my im- 45 proved sheet gage.

Throughout the various views of the drawings similar reference characters designate similar parts.

In the preferred embodiment of my in- 50 vention, as disclosed in the accompanying drawing, 1 indicates an addressing machine of a well-known type, which is provided with a plate holder 2 adapted to hold a plurality of address plates 3. In this type of 55 machine the plates 3 are successively carried below an inked ribbon 4. The sheet

to be addressed is held over the ribbon and a blow from a striker 5 causes the address to be imprinted on the sheet. The plates 3 thereafter successively pass to a supporting 60 guide 6 from whence they are manually removed. The above shows a form of well-known machine, but it will be understood that my appliance is intended to be utilized on practically any type of addressing ma- 65 chine.

Situated next to, or secured to the machine 1 is a table 7, provided at its rear edge with a guide strip 8, on which is provided a scale of markings 9, said scale con- 70 sisting of two forms of markings as 10 and 11.

Resting upon the table 7 and slidable thereon is a guide member 12 in the nature of a flat plate provided with a projecting 75 lug 13 forming a handle by which the slide 12 may be moved on its support 7.

At its rear edge the slide is provided with a scale consisting of spaced lines 10^a and 11^a, and on its side edge adjacent the addressing machine, the slide is provided with a scale consisting of the spaced markings 14. The slide is also provided with a laterally projecting sheet-supporting plate 15, which, when the sheet to be addressed is 85 in a certain position, lies over the plate holder 6 and keeps the sheet from contacting with the plates 3 resting therein.

From the foregoing, the operation of my improved device will be readily under- 90 stood.

A sheet to be addressed is placed with its edge abutting against the edge 16 of the slide 12, with the slide substantially in position as shown in Fig. 1, and the lower 95 edge of the sheet in alinement with the mark 14 nearest to the operator. After one address is applied to the sheet, the same is slid forward until its lower edge is in alinement with the next marking 14, and so on 100 until a line of addresses has been applied on the sheet, one above the other. A new line of addresses is then begun by moving the slidable guide 12 on its support until the markings 10^a or 11^a are in alinement 105 with similar markings 10 or 11 on the table. By following the arrangement above set forth the names and addresses on each sheet are similarly disposed in vertical and horizontal alinement.

It will be understood that the forms of scale markings may be varied to suit dif-

ferently sized sheets or the manner in which it is desired to place the names and addresses thereon. In the particular arrangement disclosed herein, the markings 11 and 11^a indicate the starting position of a sheet having marginal holes such as are usually found in loose leaf sheets, whereby the names and addresses placed on these sheets are so positioned that they do not encroach upon that portion of the sheet utilized when a number of the sheets are bound in their cover.

From the foregoing it is obvious that my invention is not to be restricted to the exact embodiment shown, but is broad enough to cover all structures coming within the scope of the annexed claims.

Having described my invention, what I claim is:—

- 20 1. A device of the class described comprising a support having a scale, a slidable gage member movable on said support, said gage member having an abutment for a sheet and a scale on said abutment.
- 25 2. A device of the class described comprising a support, a scale thereon, a gage member movable on said support, said gage member having scale markings adapted to be brought into alinement with the scale on the support, an abutment for a sheet on said support and spaced scale markings on said support adjacent said abutment.
- 30 3. A device of the class described comprising means for supporting a sheet to be addressed, a guide for indicating the positions of said sheet when moved in one direction, and a scale on said guide for spac-

ing names and addresses in an opposite direction.

4. A device of the class described comprising a guide for addressing machines comprising a movable member having an edge forming an abutment for a sheet, said edge having a plurality of spaced apart markings, a diagonally opposite edge having a plurality of markings, a support for said movable member and a scale thereon having markings adapted to be brought into registration with the markings on one edge of the movable member.

5. A device of the class described comprising a flat support, a strip on one of its edges having a plurality of spaced markings, a guide member movable on said support, said member having markings intended to be successively alined with the markings on the strip, said member having an edge forming an abutment for a sheet to be addressed, a sheet-supporting plate extending from said edge, and a plurality of spaced markings on said edge.

6. In a device of the class described a support having a scale, a slidable gage member movable on said support, said gage member having means coöperating with the scale to indicate various positions at which the gage member is brought to rest, said gage member having an abutment for a sheet to be addressed and a scale on said abutment.

Signed at the city, county and State of New York, this 3rd day of August, 1921.

ERNEST R. JUNGLING.
